UTILITY CART

Owen Webber, Bayonne, N. J.

Application January 11, 1950, Serial No. 138,035

2 Claims. (Cl. 211—1)

1

This invention relates to utility carts designed particularly for the handling of house utensils, such, for example, as mops, brooms, buckets, dust pans, and the like. It has for its object to provide a cart in which these utensils can be conveniently and compactly stored and transported; which is simple in make-up; which is preferably of knock-down construction for shipping or storage, and which, with its load, may be conveniently set away in a small space when not in use.

These various objects are accomplished by providing a device of generally triangular shape in plan to permit its convenient placing in the corner of a room or closet; the frame being formed of solid or hollow rods so assembled as to provide a base, vertical rods rising from the base, and an upper, generally triangular, open frame carried by said rods to receive and hold the household utensils in place, such upper frame having a demountable pan for small articles.

Figure 1 is a perspective view of the cart showing utensils of the usual type in place.

Figure 2 is a view in side elevation of the cart.

Figure 3 is a view in front elevation.

Figure 4 is a view in plan of the top frame and removable pan.

Figure 5 is a detail view showing the drainage bottom.

Figure 6 is a sectional view on substantially the line 6—6 of Figure 3 looking in the direction of the arrows.

Figure 7 is a view partly in section on substantially the line 7—7 of Figure 6 looking in the direction of the arrows.

Figure 8 is a perspective view of the top frame pan.

In the detailed description which follows, the parts disclosed in the drawings will be designated by numerals, the same numerals being used in referring to the same parts in the several views.

The bottom frame 10 is preferably formed of tubular rod of such gauge as to provide a stable structure and is preferably triangular in shape as this lends itself to convenient corner placement of the device when not in use. Carried by base 10 are casters of any usual or suitable type, mounted for turning movements in bearings on the frame. Three casters are shown, two at the base and one at the apex of frame 10, so that the unit may be readily moved from place to place. From base 10 short vertical standards 11 project, these being integral with base 10. The bottom of base 10 may be in the form of a pan 12 suitably secured to the rod members of the

2

base. Pan 12 should be provided with means for draining and as here shown has its surface slightly inclined to an opening 13 for drainage purposes.

Rising from the standards 11 and secured thereto by clamps 14, are vertical rod members 15 preferably disposed in close parallel relation. The rod members 15 may be coupled to the standards 11 of the base and to the top frame in any suitable manner, a mortise and tenon coupling being shown in Figure 7 with the clamps 14 in holding position. Rod members 15 support an open triangular frame 16 which is clamped to the upper ends of members 15 and provided with an open front, the ends of the upper frame members 16 being turned back to form utensil-retaining hook-like ends 17. Spring clips 18 will be provided on the side arms of upper frame 16 in which the handles of brooms, mops, or other utensils may be clipped to hold them in place, the lower ends of such utensils resting on the pan 12.

Removably mounted on the side arms of upper frame 16 at the apex of the triangle is a pan 19 having curved sections 20 to support it, pan 19 being designed to receive small tools or appliances used in house cleaning and repairing operations. A rod 21 extends across upper frame 16 to support the forward or base member end of pan 19. Clips 22 are provided on the base member of pan 19 to support small utensils such, for example, as brushes.

Constructed as disclosed, the unit is particularly well adapted for the use of janitors, servants, and housewives. It is compact; easily manipulated, and may be conveniently stored when not in use. Its knock-down construction permits ready assembling and disassembling so that it may be conveniently shipped and stored; it may be set up and taken down by unskilled persons, and its several parts can be made by simple bending and stamping operations.

Such changes from this specific disclosure as involve only mechanical skill and are comprehended by the appended claims defining the invention are to be regarded as within the purview of the invention.

I claim:

1. A utility cart of the class described comprising a single piece triangular base, a drainage bottom carried by said base, detachable vertical rods rising from said base, clamps coupling said base and rods, a single piece open front triangular top detachably clamped to said rods, and said top having inturned retaining hooks at the front thereof.

2. A utility cart of the class described comprising a single piece triangular base, a drainage bottom carried by said base, detachable vertical rods rising from said base, clamps coupling said base and rods, a single piece open front triangular top detachably clamped to said rods, said top having inturned retaining hooks at the front thereof, and yieldable means on said top coacting with said base for maintaining an article in a fixed position on the cart. 10
